UNITED STATES PATENT OFFICE.

EDWARD A. JOHNSTON, OF STERLING, ILLINOIS.

PLATFORM-CANVAS TIGHTENER.

No. 801,987.

Specification of Letters Patent.

Patented Oct. 17, 1905.

Application filed March 8, 1905. Serial No. 249,099.

To all whom it may concern:

Be it known that I, EDWARD A. JOHNSTON, a citizen of the United States, residing at Sterling, county of Whiteside, Illinois, have invented 5 certain new and useful Improvements in Platform-Canvas Tighteners; and I do hereby declare the following to be a full, clear, and exact description of the invention, such as will enable others skilled in the art to which it applies to make and use the same.

The invention relates to tighteners for the canvas aprons that are employed on the platforms of harvesting-machines. In this class 15 of devices it is important that both edges of the canvas be held under the same tension in order to prevent buckling of the same and so as to cause it to run evenly and straight instead of shirring off toward one end of the roller.

With these ends in view the invention consists in the particular means hereinafter described and illustrated for causing the roller at the inner end of the platform to be held under a normal spring-pressure tending 20 constantly to move it away from the roller at the outer end of the platform and arranged so as to bear with equal tension upon both ends of the movable roller so as to preserve its parallelism with the stationary roller at the other 25 end of the platform.

The invention is illustrated in the accompanying drawing, which shows in plan view the platform-frame of a harvester having the invention applied.

In the drawing, *a* and *b* denote, respectively, 35 the front and rear side boards of the platform. The stationary roller is located at the outer end of the platform and is denoted by *c*, and at the inner end of the platform the movable 40 roller is mounted with its gudgeons journaled in slides *e e*, that move in ways provided for them on the inner sides of the platform-boards *a* and *b*.

The platform-canvas is not illustrated; but 45 it will be understood that it runs over the rollers *c* and *d*, with its upper surface moving constantly toward and over the inner roller and its front and rear edges supported by the strips *f f* on the side boards *a* and *b*.

The roller-supporting slides *e e* are provided 50 with transversely and inwardly extending projections *g g* at the ends opposite the roller-bearings, and levers *h h* are pivoted to the platform side boards *a* and *b* near the outer 55 ends of the roller-slides so as to bear against

these projections. By varying the length of the projections *g g* the distances of the points of contact of the projections with the levers *h h* from the pivots of said levers may be changed, and thereby the extent of movement 60 of the slides *e e* regulated. The levers *h h* are extended inwardly toward each other and are connected at their inner ends by a slot-and-pin connection *i*, so that any movement of one lever will cause a movement of the other lever 65 corresponding therewith in direction and extent. As before stated, these levers bear against the projections *g g* of the roller-slides *e e*, and a spring *j*, preferably a coiled spring, is pivotally connected at one end to one of the 70 platform side boards, here shown as the rear side board *a*, and at its other end reacts against a bracket *k*, that is adjustably secured to one of the arms *h* and projects outward laterally therefrom on the side toward the 75 outer end of the platform, as shown in the drawing. The reaction of this spring forces the levers *h h* toward the inner end of the platform and causes them to bear with an elastic pressure on the projections of the roller-slides, and the levers being of equal length and being connected at their inner ends, as above described, tending to move the slides inward with a uniform pressure.

When the platform-canvas is applied to the 85 rollers, the levers *h h* are straightened out into the position shown in dotted lines in the drawing. This permits the roller *d* to move slightly toward the fixed roller, and after the ends of the canvas have been connected in 90 the usual manner the release of the levers *h h* by pushing on the roller-slides moves the inner roller *d* into the position shown in full lines and tightens the canvas.

The adjustability of the bracket *k* provides 95 for varying the tension of the spring *j*, and the range of movement of the roller-slides may be regulated by making the projections *g g* of proper length.

Such being the construction of the tightener 100 it will be noted that the same amount of pressure and the same movement will be effected at each end of the roller and that the parallelism of the movable and stationary rollers will be preserved. It is also noticeable 105 that the construction is simple, easily installed and adjusted, and efficient in operation.

Having thus described the invention, what I claim is—

1. A platform-canvas tightener, comprising 110

ing, in combination with the platform, outer and inner rollers *c*, *d*, roller-slides *e*, *e* having projections *g*, *g* at their outer ends, and spring-pressed levers *h*, *h*, connected together at 5 their inner ends and bearing on the projections of the roller-slides.

2. A platform-canvas tightener, comprising, in combination with the front and rear side boards of the platform, outer and inner rollers *c*, *d*, roller-slides *e*, *e*, in which the inner roller is mounted and having projections *g*, *g* at their outer ends, and levers *h*, *h* pivoted at their outer ends to the side boards of the platform and bearing against said projections, said levers being connected together at their inner ends so as to move together equally and in the same direction.

3. A platform-canvas tightener, comprising, in combination with the front and rear side boards of a harvester-platform, outer and inner rollers *c*, *d*, roller-slides *e*, *e* in which the inner roller is journaled, said slides having projections *g*, *g* at their outer ends, levers *h*, *h* pivoted at their outer ends to the platform side boards and bearing against the projections of the roller-slides, said levers being connected at their inner ends by a pin-and-slot connection *i*, and a spring *j* pivoted to one of the side boards and bearing against a 30 bracket projecting from the outer side of one of the levers.

4. A platform-canvas tightener, comprising outer and inner rollers, one of said rollers being mounted in bearings adapted to slide longitudinally relative to the canvas, spring-pressed levers connected together at their inner ends and pivoted at their outer ends, each of said levers engaging with one of said bearings between its pivot and inner end.

5. A platform-canvas tightener, comprising, in combination with the front and rear members of the platform, outer and inner rollers, sliding bearings in which the inner roller is mounted, and levers pivoted at their outer ends to said platform members and engaging with said sliding bearings, said levers being connected together at their inner ends so as to move together equally and in the same direction. 40

6. A platform-canvas tightener, comprising, in combination with the front and rear members of the platform, outer and inner rollers, sliding bearings in which the inner roller is mounted and levers pivoted at their outer ends to said platform members and engaging 45 with said sliding bearings, said levers being connected together at their inner ends so as to move together equally and in the same direction, and a spring operative to move said levers in one direction. 50

7. In a platform-canvas tightener, the combination of front and rear platform members, outer and inner rollers, sliding bearings in which the inner roller is mounted, and levers pivoted at their outer ends to said platform members and engaging with said sliding bearings, said levers being connected together at 65 their inner ends so as to move together equally and in the same direction, and a spring operative between one of said levers and one of 70 said platform members to move said levers in one direction.

In testimony whereof I affix my signature in presence of two witnesses.

EDWARD A. JOHNSTON.
